UNITED STATES PATENT OFFICE.

JAMES B. ROGERS, OF CHICAGO, ILLINOIS.

LATCH CONSTRUCTION.

Application filed May 23, 1921. Serial No. 471,538.

To all whom it may concern:

Be it known that I, JAMES B. ROGERS, a citizen of the United States, residing at Chicago, in the county of Cook and State 5 of Illinois, have invented new and useful Improvements in Latch Constructions, of which the following is a full, clear, concise, and exact description, reference being had to the accompanying drawing, forming a 10 part of this specification.

My invention relates to latch construction.

One of the objects of my invention is to provide an improved latch which will be 15 positive in its action.

A further object of my invention is to provide a latch construction in which the latching member has a combination sliding and pivotal motion.

20 A further object of my invention is to provide a latch construction in which the latching member is disengaged by pushing it inwardly and swinging it upwardly.

25 A further object of my invention is to provide an improved latch construction in which the latching member is held in latching position by a retaining member, which retaining member is released by the member which actuates the latch.

30 Further objects will appear from the detailed description to follow and from the appended claims.

In the drawings in which several embodiments of my invention are shown—

35 Fig. 1 is a side elevation of a latch construction showing the latching member in latching position;

40 Fig. 2 is a view of the construction shown in Fig. 1 with the latching member in unlatched position;

Fig. 3 is a side elevation showing another form of latch construction;

45 Fig. 4 is a top plan view of the construction shown in Fig. 3;

Fig. 5 is a side elevation showing another form of latch construction, parts being shown in section;

50 Fig. 6 is a side elevation of the construction shown in Fig. 5 with the latching member starting to unlatch;

Fig. 7 is a side elevation showing another form of latch construction;

Fig. 8 is a top plan view of the construction shown in Fig. 7;

55 Fig. 9 is a side elevation showing a latch construction suitable for elevator work; and

Fig. 10 is a section substantially on the line 10—10 of Fig. 9.

Referring first to Figs. 1 and 2, the construction shown therein comprises a latching member 10, a pivoted hook 11 with which the latching member 10 engages, means 12 for mounting the latching member 10 for pivotal and sliding movement, a pivoted retaining member 13 for holding the latching member 10 in latching position, and pivoted actuating member 14 for releasing the retaining member 13, and actuating the latching member 10 to move it from latching to unlatching position, and vice versa.

The hook member 11 is pivotally mounted on a pin 15, and is counterweighted as indicated at 16 to normally hold this hook in the position shown in Figs. 1 and 2. Stops 17 and 18 are provided to limit the pivotal movement of the hook 11. As will be explained hereinafter, the latch construction would be operative even if the hook 11 were rigid, but the hook is pivotally mounted in order that the latch may be brought into latching position without the necessity for any pivotal movement of the latching member 10.

In order to facilitate an understanding of the movement, it is here stated that in the construction shown in Fig. 1 there are four fixed pivotal points or axes, as follows: the axis of the pin 15 on which the hook member 11 is pivotally mounted, the axis of the pin 19, about which the latching member 10 is pivotally and slidably mounted, the axis of the pin 20, on which the actuated member 14 is pivotally mounted, and the axis of the pin 21 on which the retaining member 13 is pivotally mounted. The retaining member 13, when in retaining position as shown in Fig. 1, holds the latching member 10 in horizontal latching position by engagement with the shoulder 22 on the latching member 10. In order that this retaining member 13 may be lifted to release the latching member 10 so that the latter can be moved to unlatching position,

100 a lost motion connection is provided between the actuating member 14 and the latching member 10, so that the first part of the movement of the actuating member causes no movement of the latching member, and this initial movement of the actuating member 14 is utilized to release the retaining member 13, the actuating member being 105 provided with a spiral edge cam 23 which

engages underneath the pivoted retaining member 13, and lifts this retaining member upward out of engagement with the shoulder 22, during the initial movement of the actuating member 14. The lost motion connection between the actuating member 14 and the latching member 10 is effected by providing the latching member 10 with a pin 24, for engagement with an arcuate slot 25, in the actuating member 14.

Stops 26 and 27 may be provided to limit the movement of the holding member 13, and prevent it being raised too high or dropping too low.

15 The means 12 for mounting the latching member 10 for pivotal and sliding movement comprises a pair of rollers 28 mounted in a rocker 29, which rocker is pivotally mounted on the pin 19. The rollers 28 operate in a slot 30 in the latching member 10, and provide an anti-friction mounting for the latching member.

In using the device, if the parts are in position shown in Fig. 1, and it is desired 25 to move them to unlatched position, the operator takes hold of the handle 31 of the operating member 14 and moves it to the right, from the position shown in Fig. 1 to the position shown in Fig. 2. The first 30 part of the movement of the actuating member 14 lifts the retaining member 13 without moving the latching member 10.

At about the time the holding member 13 is lifted out of engagement with the shoulder 23, or shortly thereafter, the end wall of the arcuate slot 25 engages the pin 24, and starts the movement of the latching member 10. The movement of the hook end 32 of the latching member is a somewhat peculiar 40 one, as indicated by the dotted line 33 in Fig. 2, which shows the path of the point of the hook 32. As shown by this dotted line path, the first movement of the latching member 10 is inwardly at a slightly upward 45 incline to easily effect the disengagement of the hook end 32 of the latching member 10 from the hooked end 34 of the member 11. Further movement of the actuating member 14 brings the latching member 10 to the position shown in Fig. 2. It will be 50 noted that this construction is suitable for an elevator door, since if the latching constructure is mounted on a sliding door 34, the movement of the actuating member 31 55 is such that the movement of this member to unlatch it, if continued, would cause the door to slide open. In closing the door and moving the latching member 10 to closing position, it is immaterial whether 60 the latching member 10 is moved to horizontal position before or after the door is closed. If the door is closed first, the latching member 10 can be moved to closed position by swinging the actuating member 65 14 from the position shown in Fig. 2 to

the position shown in Fig. 1. If, however, the latching member is swung to the position shown in Fig. 1, before the door is closed, the hook member 11 will simply be depressed by the engagement of the slanting surface 35 70 of the latching member 10 with the slanting surface 36 of the hook member 11, the shape of the hook portions 32 and 34 being such that after the hook portions pass each other, the hook portion 34 can swing up into 75 latching engagement with the hook portion 32 of the latching member 10.

The construction shown in Figs. 3 and 4, is quite similar to the construction shown in Figs. 1 and 2, except that here the latching member rides under, instead of over, the hook member if the latching member is moved to latching position before the door is closed. In this construction the retaining member 13, and the actuating member 14 may be the same as in the form previously described. In this form, however, the hook member 37 is provided with a laterally extending boss or lug 38, the outline of which is shown in dotted lines in Fig. 3, and the latching member 39 is also provided with a laterally offset boss 40, which engages the boss 38, as shown in Fig. 3. The boss 40 is hook-shaped in elevation, as shown in dotted lines in Fig. 3, and this hook-shaped portion receives the rounded portion of the boss 38. When the actuating member 14 is operated, the point of the latching member 39 follows the path indicated in dotted lines at 42, the shape of the boss 40 being such as to permit the latching member 39 to move inwardly and upwardly to disengage the boss 40 from the boss 38. The latching member 39 is pivotally and slidably mounted on a pin 43, mounted on the door 44, this pin 43 engaging the slot 45 in the latching member. The lost motion connection between the actuating member 14 and the latching member 39 is effected by means of the pin 46, which engages the slot 25 in the 100 actuating member 14.

In this form, also, it is not necessary that the door should be closed before the latching member 39 is moved to horizontal position, since if the latching member 39 is moved to horizontal position and the door is afterward moved to closed position, the slanting edge 47 of the latching member will simply ride underneath the slanting edge 48 of the boss 38, lifting up the hook member 37 until the boss 40 passes the boss 38, after which the hook member 39 will drop down into latching engagement with the latching member 39.

The construction shown in Figs. 5 and 6, is substantially the same as that shown in Fig. 1, except that in this form the latching member 48 engages a fixed pin 49, and the operating member 50 is provided with a key-control. The holding member 13 may be 125 130

the same as in the form previously described. The actuating member 50 is operated by means of a key-controlled member 51, having a lost motion connection with the 5 operating member 50 as indicated in Fig. 5, the lost motion connection being such that a complete revolution of the key-controlled member 51 will give the operating member a sufficient movement of oscillation to move 10 the latching member 48 from latching to unlatching position or vice versa. The lost motion connection between the key-controlled member 51 and the actuating member 50 is effected by providing the hub of the actuating member 51 with a chamber in which the key-controlled member 51 is mounted, the wall of this chamber being provided with a shoulder 52, which is engaged by the key-controlled member 51. Any suitable or 20 usual construction may be provided, whereby the member 51 will be key-controlled, such as a Yale lock construction shown at 53, the key-controlled member 51 being arranged to rotate with the barrel of the lock 25 53.

The arrangement is such that a complete rotation of the key such as is necessary for operating the lock 53 will move the latching member 48 from one of its extreme positions to the other.

In all of these forms, it will be noted that the first movement of the latching member is an inward movement, which readily effects the disengagement of the latching member from the hook or fastening member with which it cooperates.

The construction shown in Figs. 7 and 8 is substantially the same as that shown in Figs. 3 and 4, except as to the engagement 40 between the latching member 54 and the hook member 55. In this form the hook member 55 is bifurcated, to provide two arms 56, which straddle the latching member 54. The arms 56 are provided with laterally extending bosses 57, shown in outline in Fig. 7, which engage the ends of a transversely extending pin 58, which extends through the latching member 54 and laterally on both sides thereof. The holding member 13 and the operating member 14 may be the same as in Figs. 3 and 4. In this form, when the latching member 54 is being moved to unlatching position, its inner end moves upwardly and inwardly between the arms 56, the pin 58 moving clear of the laterally extending bosses 57 during this movement.

The latching member 54 can be moved to closed position either before or after the closing of the sliding door 59. If the door is closed before the latching member 54 is moved to latching position, this latching member will swing down into latching position from above, the inner end of the latching member 54 moving down between the

arms 56 and the pin 58 moving into latching relation with respect to the bosses 57. If, however, the latching member 54 is swung to horizontal position before the door is closed, and the door is afterward closed, 70 the end of the pin 58 will simply ride underneath the slanting ends 60 of the arms 56, lifting the hook member 55 until the ends of the pin 58 pass the laterally extending bosses 57, when the hook member 55 will drop 75 down into latching relation with respect to the pin 58.

The construction shown in Figs. 9 and 10 is substantially the same as that shown in Figs. 5 and 6, except that in this form a gear transmission 58 is provided between the operating lever 59 and the oscillating member 60, whereby the oscillating member 60 will be made to travel through a greater are than is traversed by the operating handle 59. This enables a relatively short movement of the operating handle 59 to effect the necessary oscillatory movement of the member 60 for operating the retaining member 13, and the latching member 48. This gear transmission 58 comprises a segmental gear 60^a mounted on the shaft 61 on which the handle 59 is mounted, and a pinion 62 meshing the segmental gear 60^a, and secured to the oscillatory member 60 95 which operates the retaining member 13 and the latch member 48. It will be noted that this construction also is suitable for an elevator door, since if the latching construction is mounted on a sliding door, the movement of the actuating handle 59 is such that a movement of this member to unlatch the door, if continued, would cause the door to slide open. As the gear ratio between the gear 60 and the pinion 62 is shown as about 2 to 1, it is only necessary to move the handle 59 through about 45 degrees to effect the necessary movement for the operation of the latching member 48.

Having thus described my invention, 110 what I claim as new and desire to secure by Letters Patent of the United States is:

1. A latch construction comprising a hook member, a pivoted hook operating member, means for mounting said hook for pivotal and sliding movement about a support eccentric of the axis of the pivoted hook operating member, said hook operating member having a pivotal connection with the hook member eccentric to the axis of the hook operating member.

2. A latch construction comprising a hook member, a catch for holding said hook member in latching position, a pivoted member for operating both hook and catch, means for mounting said hook for pivotal and sliding movement about a support eccentric to the axis of the operating member, said operating member having a lost motion connection with the hook member eccentric to 130

the axis of the member, said operating member acting to release the catch during its lost motion movement and acting to give the hook member its pivotal and sliding movement after its lost motion movement.

3. A latch construction comprising a hook member, a catch for holding said hook member in latching position, a pivoted member for operating both hook and catch, means for mounting said hook for pivotal and sliding movement about a support eccentric to the axis of the operating member, said operating member having a lost motion connection with the hook member eccentric to the axis of the member, said operating member acting to release the catch during its lost motion movement and acting to give the hook member its pivotal and sliding movement after its lost motion movement, said lost motion connection comprising a pin and slot connection, said slot being arcuate with its center in the axis of the operating member.

4. A latch construction comprising a movable hook member, a holding member over which said hook member engages, means for mounting said hook member for pivotal and

sliding movement longitudinally towards said holding member and laterally away from said holding member for releasing the hook member from the holding member and actuating means for positively effecting said longitudinal and lateral movement.

5. A latch construction comprising a movable hook member, a holding member over which said hook member engages, means for mounting said hook member for pivotal and sliding movement longitudinally towards said holding member and laterally away from said holding member for releasing the hook member from the holding member and actuating means for positively effecting said longitudinal and lateral movement, said actuating means comprising a pivotally mounted hook operating member having a pivoted connection with said hook member for unlatching it and said mounting means comprising a support eccentric to the axis of said pivotally mounted operating member on which support said hook member has a pivotal and sliding movement.

In witness whereof, I have hereunto subscribed my name.

JAMES B. ROGERS.
